[57] CLAIM

The ornamental design for a combined camera and eyeglasses, as shown and described.

DESCRIPTION

FIG. 1 is a front elevational view of a pair of glasses incorporating a camera device;

FIG. 2 is a right side elevational view thereof;

FIG. 3 is a rear elevational view thereof;

FIG. 4 is a left side elevational view thereof; and

FIG. 5 is a top plan view thereof.

The focus and shutter release controls are shown broken-away in FIGS. 1-4 to indicate indeterminate length.

Fig. 5
